ADELBERT E. HALL, OF BAY CITY, MICHIGAN.

VALVE GEAR.

Application filed September 27, 1919. Serial No. 328,762.

This invention relates to improvements in valve gear, and more particularly to the valve gear as used on railroad locomotives.

One object of the invention, is to arrange 5 the valve gear to provide for a more perfect distribution of steam in the cylinders by controlling the valves from the cross head thus effecting a more uniform and even flow of power.

10 Another object is to provide means whereby the valve may be caused to pause or halt at the ends of the stroke thereby effecting a longer port opening.

A still further object is to mount it rigidly 15 on the frame, and simplify the valve gear by eliminating a number of parts which are used in making up the valve gear which is now in general use.

With the above and other objects in view, 20 the present invention consists in the combination and arrangement of parts hereinafter more fully described, illustrated in the accompanying drawings, and more particularly pointed out in the appended claims, it 25 being understood that changes may be made in the form size, proportion and minor details without departing from the spirit or sacrificing any of the advantages of the invention.

30 In the drawings:

Fig. 1 is a fragmentary side view of a locomotive with my improved valve gear in place thereon.

Fig. 2 is a top plan view thereof showing 35 it applied to both valves.

Fig. 3 is an end view of the valve gear.

Fig. 4 is a detail of the control levers in two positions, the dotted lines showing the go-ahead position.

40 Figure 5 is an elevation of a portion of the valve mechanism showing the same in two positions and illustrating the manner in which the valve is caused to pause or dwell.

Figure 6 is a detail transverse sectional view taken through the main rod at the rear of the crosshead in Fig. 5 partly in section.

Figure 7 is an elevation partly in section showing the valve gear mechanism in two positions.

50 Figure 8 is a detail perspective view of the bell crank lever.

Figure 9 is a detail perspective view of the

link which connects the bell crank lever with the main rod.

Referring now more particularly to the drawings in which is illustrated the preferred embodiment of the invention, 3 designates a locomotive cross head which is slidably mounted in and guided by a frame 2 of the usual construction. A pitman or main rod 5 is pivotally connected at its front end with the cross head 3 and at its rear end with the drive wheels 4. The usual valves 6 are of the ordinary construction and form no part of the present invention.

Rigidly mounted on the frames 7 are the brackets 8 extending rearwardly from the frame, and it will be readily understood that the frames 7 are located one on each side of the boiler, and are connected together in any suitable manner.

Pivotedly mounted on the cross head 3 at the point 9 is a connecting rod 10 extending rearwardly from the cross head to the lower end of a cross head lever 11 and pivoted at this rear end to the latter by a pin 12. This lever 11 which is actuated by the cross head 3 extends upwardly and has pivoted to it at a point intermediate of its ends, the lower end of a radius link 13, the upper end of the said link being connected to a reversing arm 14 at the point 15. The upper end of the reversing arm 14 is connected to the front end of a reach rod 16 and the lower end of the reversing arm is rigidly set on a transverse shaft 17 extending under the boiler from one side of the locomotive to the other. The reverse shaft 17 is journaled in outer bearings of curved rearwardly extending portions of the brackets 8.

The brackets 8 are provided at points intermediate of their ends with transversely aligned bearings 18 in which are journaled transversely disposed interlocking shafts 19 and 19^a, each consisting of a tubular section and a reduced solid section. These shafts are of like construction and each shaft has its reduced solid portion extending through the tubular portion of the other shaft and journaled in the same. By this construction the shafts 19 and 19^a operate on a common axis and each extends entirely across the locomotive and is sufficiently exposed to provide means for mounting or connecting the arms

of the shafts with their respective shafts without one shaft interfering with the operation of the other. Also, a compact construction is provided in which each shaft assists in supporting and reinforcing the other shaft. The arms 20 are rigidly mounted on and extend rearwardly from the tubular portions of the shafts 19 and 19^a, and have bifurcated outer or free ends in which are pivoted the upper ends of cross head levers 11. Each shaft is connected at one end with one of the cross head levers 11 and at the other end with a combination lever 23 by means of an arm 20^a. The arms 20^a depend from the reduced solid portions of the shafts 19 and 19^a and are pivotally connected to the upper ends of the combination levers 23. Pivotally mounted on the crosshead 3 at the point 25 is a bell crank lever 26 consisting of an approximately horizontal rearwardly extending short arm and a depending relatively long approximately vertical arm. The lower end of the depending vertical arm of the bell crank lever 26 is connected by a link 27 with the lower end of the combination lever 23, and the short upper arm of the bell crank lever 26 is connected to the pitman or main rod 5 at 28 by means of a link 29. The valve rod 30 is also pivoted to the upper portion of the combination lever 23 at 31, a short distance from the upper end of the said combination lever 23. It will thus be obvious that the bell crank lever 26 will be oscillated on its pivot 25 of the crosshead 3 by the pitman or main rod 5 and that when the crank end of the drive wheel is moving backwardly or forwardly and is carrying with it the main rod 5, there will be little or no movement of the bell crank lever 26, but at the end of the stroke of the main rod 5 the vertical or up and down movement of the crank or wrist pin of the drive wheel will produce a rapid upward or downward movement of the main rod 5 and a consequent rapid movement of the bell crank lever 26. It will be clear that this will produce a rapid opening and closing movement of the valve and cause the same to dwell or pause between the opening and closing movement and will also result in a rapid port opening and closing and cause the steam to act on the piston a maximum length of time during each stroke.

In the illustration as shown in Fig. 1 the mechanism is in the reverse position, while as shown in the dotted lines in Fig. 4 the mechanism is in the go-ahead position, which will of course admit the steam to the opposite side of the piston.

In Figure 5 of the drawings the valve gear is illustrated in two positions to show that the valve will dwell at lead positions. When the main rod 5 is in the position shown in full lines in Figure 6, the cross head and other mechanism is in the position as shown, and as the wheels revolve and the main rod 5

assumes the position shown in dotted lines the cross head, together with the bell crank lever 26 and the link 29, will also assume the positions shown in dotted lines. The end 26^a of the bell crank lever 26 will not move 71 longitudinally due to the fact that the link 29, which is secured to the main rod, rocks the bell crank lever 26 on the pivot 25 so that the point 26^a does not move in a longitudinal direction, even though the cross head 75 does travel back a limited distance as shown in dotted lines.

From the foregoing description it will be seen that I have perfected an extremely simple and effective valve gear, eliminating a 80 number of parts such as the radial link, the eccentric or secondary crank on the main wrist pin, eccentric rods and bell cranks used on the types of valve gear now in general use, and it will be observed that the movement 85 of the valve is entirely controlled by the cross heads and eliminates all errors caused from driving axle oscillations.

I claim:

1. In combination with a locomotive engine, a valve gear including transverse coaxially arranged shafts adapted to extend across the engine and each consisting of a reduced section and a tubular section, of substantially uniform length having their adjacent ends spaced apart at the center of each shaft, the tubular section of each shaft being sleeved on the reduced section of the other shaft and the said shafts being provided with oppositely bowed portions rigidly connecting the reduced and tubular sections of each shaft with each other, means located at opposite sides of the engine for connecting the said shafts with the crossheads of the engine, combination levers located at opposite sides of the locomotive and connected with the said shafts, and means for connecting the combination levers with the main rods of the locomotive and with the engine valves, said combination levers operating to supply lap and lead motion. 90 95 100 105 110

2. In combination with a locomotive engine, a valve gear including transversely disposed coaxially arranged shafts having interfitted reduced and tubular sections, of substantially uniform length having their adjacent ends spaced apart at the center of each shaft, the tubular section of each shaft being sleeved on the reduced section of the other shaft said sections being of a substantially uniform length and spaced apart at their adjacent ends at the center of each shaft, and bowed portions rigidly connecting the sections of each shaft with each other, crosshead levers located at opposite sides of the engine and connected with the crossheads of the latter, arms extending from the shaft and pivoted to the crosshead levers and connecting one of the sections of each shaft with one of the cross head levers, and means for connecting the 115 120 125 130

other section of each shaft with one of the main rods of the engine for supplying lap and lead motion.

3. In a locomotive engine, a valve gear including transversely disposed coaxially arranged shafts having interfitting reduced and tubular sections, said sections being of substantially uniform length and having their adjacent ends spaced apart at the center of each shaft, and central connecting portions rigidly connecting the sections of each shaft with each other, means located at opposite sides of the locomotive engine for connecting one of the sections of each shaft with one of the crossheads of the engine, said means including a crosshead lever pivoted intermediate of its ends, a link connecting one end of the cross head lever with one of the crossheads, an arm extending from one of the shafts and connected to the other end of the crosshead lever, means for connecting the other section of each shaft with one of the main rods of the engine for supplying lap and lead motion, and reversing mechanism connected with the crosshead levers.

4. In combination with a locomotive engine, a valve gear including transversely disposed coaxially arranged shafts having interfitting reduced and tubular sections, said sections being of substantially uniform length and having their adjacent ends spaced apart at the center of each shaft, and central connecting portions rigidly connecting the sections of each shaft with each other, means for connecting one section of each shaft with a crosshead of the engine, the latter means comprising an arm carried by such section, a crosshead lever located in rear of the adjacent crosshead and extending above the adjacent main rod of the locomotive and pivoted at its upper end to the said arm, and a connecting rod extending from the lower end of the adjacent crosshead and pivoted to the same, means for connecting the other section of each shaft with a main rod of the engine for supplying lap and lead motion, and reversing mechanism having a radius link connected to the crosshead lever intermediate of the ends thereof at each side of the engine.

5. In combination with a locomotive engine, a valve gear including transversely disposed coaxially arranged shafts extending across the engine, said sections being of substantially uniform length and having their adjacent ends spaced apart at the center of each shaft, and central connecting portions rigidly connecting the sections of each shaft with each other, means for connecting one of the sections of each shaft with the adjacent crosshead of the engine and means for connecting the other section of the shaft with one of the main rods of the engine, the latter means comprising a shaft arm, a combination lever pivoted to said arm, and a link connecting the combination lever with the adja-

cent main rod, and means for connecting the combination levers with the valves of the engine.

6. In a locomotive engine, a valve gear including transversely disposed coaxially arranged shafts extending across the engine, said sections being of substantially uniform length and having their adjacent ends spaced apart at the center of each shaft, and central connecting portions rigidly connecting the sections of each shaft with each other, means for connecting each of the shafts with one of the crossheads of the engine, and separate means for connecting each of the said shafts with a main rod of the engine, the latter means comprising a shaft arm, a combination lever pivoted to said arm, and a lever pivotally mounted on a crosshead and connected with the adjacent main rod and with the combination lever and means for connecting the combination levers with the valves of the engine.

7. In combination with a locomotive engine, a valve gear comprising brackets located at opposite sides of the engine and provided with intermediate and terminal bearings, coaxially arranged transverse shafts journaled in the intermediate bearings of the said brackets, said sections being of substantially uniform length and having their adjacent ends spaced apart at the center of each shaft, and central connecting portions rigidly connecting the sections of each shaft with each other, means for connecting each of the shafts with one of the crossheads of the engine, said means including shaft arms, crosshead levers pivoted to the said arms and connecting rods extending from the crossheads to the crosshead levers, reversing mechanism including a transverse reverse shaft journaled in the terminal bearings of the said brackets and provided with reverse arms and radius links connecting the reverse arms with the crosshead levers, and combination levers connected with the said shafts and with the main rods of the engine for supplying lap and lead motion.

8. In combination with a locomotive engine, a valve gear comprising aligned brackets located at opposite sides of the locomotive, transversely disposed co-axial shafts extending across the engine and each consisting of a reduced section and a tubular section of substantially uniform length, and having their adjacent ends spaced apart at the center of the shafts, the tubular section of each shaft being sleeved on the reduced section of the other shaft and journaled in one of the said brackets, and the said shafts being provided at their centers with oppositely bowed portions rigidly connecting the sections of each shaft, a crosshead lever located in rear of the adjacent cross head and extending above the adjacent main rod of the locomotive, an arm extending from one of the shafts and pivoted

to the upper end of the crosshead lever, a link connecting the lower end of the crosshead lever with the adjacent crosshead, a combination lever, a shaft arm connected with the other shaft and pivoted to the upper end of the combination lever, a substantially L-shaped lever pivotally mounted on the adjacent crosshead, links connecting the arms of

the L-shaped lever with the adjacent main rod and with the combination lever, means for connecting the combination lever with the valve of the locomotive, and reversing mechanism having a radius link connected with the crosshead lever.

10

In testimony whereof I affix my signature.

ADELBERT E. HALL.
